UNITED STATES PATENT OFFICE.

WILLIAM JOHN STEWART, OF BELFAST, IRELAND.

EXCAVATING FOR CONCRETE PILES, &c.

No. 872,093.

Specification of Letters Patent.

Patented Nov. 26, 1907.

Application filed June 25, 1907. Serial No. 380,761.

To all whom it may concern:

Be it known that I, WILLIAM JOHN STEWART, of Ormeau Road, Belfast, in the county of Down, Ireland, building and engineering contractor, have invented certain new and useful Improvements in Excavating for Concrete Piles and other Such Work, of which the following is a specification.

This invention has reference to improvements in excavating for concrete or other piles, well sinking and other work of a similar kind, such as the sinking of ca'ssons, excavating shafts, and for mining and many other purposes, and consists essentially in driving through the material a tube with a suitable cutting edge, and fitting within same an inner tube to receive the excavated material, as it is dislodged by the sinking of the outer tube by percussive or other action, and discharging same by the withdrawal of said inner tube periodically or otherwise as found most suitable. When the hole has been sunk to a sufficient depth, the inner tube is withdrawn and, if a concrete pile is to be formed, the liquid concrete is poured into the outer tube. Before the concrete has set, this tube is removed and may be readily cleaned for use in another excavation.

In order that others skilled in the art to which my invention relates may properly understand same, I have hereunto appended two sheets of illustrative drawings in which

Figure 1 is an inverted plan and Fig. 2 an elevation partly in section of the lower end of the outer tube. Fig. 3 is a sectional plan on the line 3—3 in Fig. 4 which is a sectional elevation, showing the inner tube with contracted mouth within the outer tube. Fig. 5 is also a sectional plan on the line 5—5 in Fig. 6 showing the inner tube with a different form of contracted mouth. Fig. 7 is an elevation of the lower end of the inner tube furnished with jaws shown also at right angles in Fig. 8 which is a sectional elevation of the lower ends of both tubes. Figs. 9 and 12 are elevations partly in section of the lower ends of the outer and inner tubes illustrating modified arrangements for effecting the same object of contracting the entrance to the lower end of the inner tube, while Figs. 10 and 13 are inverted plans of the lower end of the inner tube corresponding to Figs. 9 and 12 and Figs. 11 and 14 show details.

The outer tube 1 to be driven into the soil or other material is fitted at its lower end with a circumferential shoe 2 or chisel cut-

ting edge riveted or otherwise secured to it. This consists of a steel or other metal ring 2 angled downwards and inwards or only angled one way from its greatest circumference 60 to form a cutting edge 3 and checked or formed with a shoulder 4 on its inner surface to form an abutment for the lower end of the tube 1 and also for a check or shoulder 5 on the lower part of the inner tube 6, and as 65 shown in Fig. 4 having a second check or shoulder 7 formed near its lower edge to form abutment for the lower end of the inner tube 6, and prevent the excavated material getting between the tubes. The lower end of 70 the ring 2 is also angled inwards and upwards to produce a good cutting edge.

For excavating through hard ground, clay or other material, such as sandstone or other mineral, the lower end or cutting edge 3 of 75 the outer tube is preferably furnished with conical pointed teeth 8 at spaced distances apart around the cutting edge 3 but these teeth may be dispensed with for other work.

The inner tube 6 which fits loosely within the outer tube 1 is made in two longitudinal halves, the adjacent edges of the halves being formed with checks, as indicated at 9 in Fig. 3, to allow of a little play or expansion and contraction of the inner tube to tighten on 80 and grip the material. The inner tube, may however be made in one if desired.

As illustrated by Figs. 3 and 4 the lower end of the inner tube is formed of a ring 10 either in one or two parts which is riveted or 90 otherwise secured to it. This ring 10 is checked on its outer surface to abut on the checks or shoulders 4 and 7 of the outer tube 1 and is formed with a curved swell or projection all round to provide a contracted 95 mouth, which may be varied to suit the material being excavated. As the material is excavated it passes up through the contracted mouth and is held by it within the inner tube 6 while that is being withdrawn by chains attached to its upper end, or by any suitable means, to be emptied. To cause the two halves of the inner tube 6, when so constructed, to compress and grip the excavated material, levers or links 11 are jointed to 100 their inner surfaces near the lower end, the other ends of which links are connected to a rod 19, or it may be a chain or other means, as shown in Fig. 4, so that when being drawn up the two halves are drawn together and 105 grip the material between them. The cavity so excavated may be filled in with concrete

or otherwise according to the work being done.

Figs. 5 and 6 illustrate a modified form of contracted mouth which is arranged as follows:—Four or other number of projections or guide bars 12 are secured on the inner surface of the inner tube 6 from the upper to near the lower end where they are beveled off, as shown in Fig. 6. A short length of tube 13, conoidal or nozzle shaped and having notches 14 formed in its lower edge corresponding to the projections 12, is passed down to the bottom of the inner tube and is there given a slight turn to lock it and prevent it rising with the excavated material. This nozzle 13 rests upon a ledge or shoulder 15 at the lower end of the inner tube 6. More than one conoidal tube 13 may be used within the inner tube 6 at distances apart if desired, and their angle of inclination may be varied to suit the circumstances.

As illustrated by Figs. 7 and 8 instead of making the inner tube 6 in two longitudinal parts, its lower end only is so formed as a pair of jaws 16 jointed to it by hinges 17, and connected by the levers or links 11 to the rod 19, or it may be a chain, by which the jaws are made to close on the material. The open position is shown by the dotted lines in Fig. 7. Quadrant shaped plates 18 are secured to the upper part of the jaws to close any opening between them and the end of the inner tube 6.

Instead of forming or fitting the lower end 35 of the inner tube 6 with a contracted mouth or closing jaws to retain the excavated material, as shown in Figs. 9 to 11 it is provided with a cross bar or plate 20, or it may be more than one, passing from side to side at 40 the bottom and formed as a knife edge 21 below and a broader part above to support the material. To support the bar 20 in position two rings 22 and 23 are secured within the lower end of the tube 6 and the flat ends 45 24 of the bar are entered through the openings 25 and then turned in the space between the rings 22 and 23 to the position shown.

Portable and interchangeable ends having a variety of arrangements of cross bars may 50 be provided so that the variety appropriate to the soil or material being worked may be secured to the lower end of the inner tube.

As illustrated by Figs. 12 to 14 bars 20 in cruciform shape are made in one with a ring 55 28 having projections 26 which are entered into the bayonet joint slots 27 to be held securely in position, and any variety of such portable ends may be provided.

The excavated material may be discharged from the tube by withdrawing the bars when 60 these are inserted singly, or by removing the ends when these are made portable and interchangeable.

What I claim as my invention and desire to secure by Letters Patent is as follows:— 65

1. In excavating for concrete piles, and other such work, the combination comprising an outer sinking tube provided with a cutting shoe and an inner tube, to receive and periodically discharge the excavated material, substantially as set forth. 70

2. In excavating for concrete piles, and other such work, the combination comprising an outer sinking tube provided with a cutting shoe and an inner tube having its lower end contracted, to receive and periodically discharge the excavated material, substantially as set forth. 75

3. In excavating for concrete piles, and other such work, the combination comprising 80 an outer sinking tube provided with a cutting shoe, having a lower sharp cutting edge and an inner annular shoulder, to support an inner tube to receive and periodically discharge the excavated material, substantially 85 as set forth.

4. In excavating for concrete piles and other such work the combination of an outer sinking tube, provided with a cutting shoe formed with a lower sharp cutting edge and 90 pointed teeth and an inner tube, to receive and periodically discharge the excavated material, substantially as set forth. 95

5. In excavating for concrete piles, and other such work, the combination comprising 95 an outer sinking tube, provided with a cutting shoe, and an inner tube, to receive and periodically discharge the excavated material, having its lower end contracted by the insertion of a bar or bars formed as a knife 100 edge below substantially as set forth.

6. In excavating for concrete piles, and other such work, the combination comprising an outer sinking tube, provided with a cutting shoe, and an inner tube, to receive and 105 periodically discharge the excavated material, fitted with portable and interchangeable ends formed of bars with knife edges below substantially as set forth.

In testimony whereof I have signed my 110 name to this specification, in the presence of two subscribing witnesses.

WILLIAM JOHN STEWART.
